Primary Examiner—Antoine D. Davis

(57) **CLAIM**

An ornamental design for a thermostat housing, as shown and described.

DESCRIPTION

FIG. 1 is a perspective view of a thermostat housing;

FIG. 2 is a front elevation view of the thermostat housing of FIG. 1;

FIG. 3 is a left elevation view of the thermostat housing of FIG. 1;

FIG. 4 is a right elevation view of the thermostat housing of FIG. 1;

FIG. 5 is a top view of the thermostat housing of FIG. 1;

FIG. 6 is a bottom view of the thermostat housing of FIG. 1;

FIG. 7 is a back view of the thermostat housing of FIG. 1;

FIG. 8 is a front view of another thermostat housing;

FIG. 9 is a front view of another thermostat housing;

FIG. 10 is a front view of another thermostat housing; and,

FIG. 11 is a front view of another thermostat housing.

The portions illustrated in broken lines on the figures are for illustrative purposes only and form no part of the claimed design.
